UNITED STATES PATENT OFFICE.

JULIUS H. RICHARDS, OF NEWARK, NEW JERSEY.

ENGINE-STARTING DEVICE.

1,310,091.

Specification of Letters Patent. Patented July 15, 1919.

Application filed March 16, 1918. Serial No. 222,979.

To all whom it may concern:

Be it known that I, JULIUS H. RICHARDS, a citizen of the United States, residing at Newark, in the county of Essex and State of New Jersey, have invented certain new and useful Improvements in Engine-Starting Devices, of which the following is a specification.

In the use of internal combustion engines on autovehicles it has become almost universal practice to crank them by means of an electric motor receiving its power from a storage battery. Various methods of applying the electric motor to the engine have been proposed and used. A very common method of engagement involves the use of a weighted pinion connected to the starting motor shaft through the medium of a sleeve and a heavy spring, the driving pinion being automatically moved into and out of engagement with the engine driven member, such as the gear on the fly wheel, when current is applied to the electric motor. Such an engagement is known as the Bendix drive.

There are certain limitations to a drive of this kind, one such being the number of teeth that may be cut on the driving pinion to get a high gear ratio of engagement, that is to say, the lower the number of teeth on the pinion with a certain fixed number of teeth on the fly wheel the greater will be the purchase of the starting motor on the engine. Another objection to the Bendix drive is the length of same and cost of manufacturing.

It is the object of my invention to produce a starting device which will be small and compact, cheap to manufacture and capable of being constructed so as to give the greatest purchase between the starting motor and the engine that is possible to obtain, the only limit being the strength of the materials.

These and other objects will be apparent after a study of the specification and drawings, in which Figure 1 is a part, plan and sectional view of my starting device in its normal position.

Fig. 2 is a plan view of one of the elements of my starting device.

Fig. 3 is a right hand view of Fig. 2. Fig. 4 is a view of the driving pinion with part broken away to show certain details.

Fig. 5 is a view of the retaining ring serving in part to hold the driving device together.

Fig. 6 is a view of the threaded nut for causing the driving pinion to move in and out of mesh with the engine driven member.

Fig. 7 is a view of a lockwasher used in coöperation with the retaining ring shown in Fig. 5.

Fig. 8 is a view of a spring lock used in the starting device.

Referring now to the details, wherein like numbers refer to corresponding parts in the various views, 1 illustrates an engine driven member, which, in the form shown, is a fly wheel, which carries gear teeth 2. 3 is the end of a starting motor shaft. The motor itself is not shown as this is no part of my invention and its functions are well understood. The shaft 3 is reduced for a portion of its length at 4 and upon this reduced portion is carried a gear wheel or driving pinion 5. In the Bendix drive the interior bore of the pinion 5 is threaded to run on a threaded sleeve but in my improved device the bore of the pinion 5 is smooth. The left hand end of the pinion 5 which I term the non-working end, since it is not in engagement with the fly wheel, has the teeth turned off down to the root and a collar 6 placed thereon and the remaining portion of the stock of the pinion 5 is spun over at 7 to hold the collar 6 rigidly in place on the pinion 5.

I will now describe the method in which the pinion 5 with the collar 6 assembled thereon, as above described, is drivingly connected to the shaft 3. A cylindrical drum 8 has one end (see Fig. 3) perforated so as to have teeth 9 to correspond in number and contour to the teeth in pinion 5. The other end of the drum is open but the surface thereof terminates in fingers 10 which have slots 11 therein, the purpose of which will be later pointed out. The extreme end of the shaft 3 is threaded at 12 with a suitable type of thread and a nut 13 is adapted to be carried thereon. The nut 13 has notches 14 corresponding in number and width to the fingers 10 of the drum 8. As shown in Fig. 1 the drum is carried on the pinion 5 in the manner already explained and the nut 13 screwed on to the threaded end 12 to proper position, when the pinion 5 and the drum 8 are slid over the shaft 3, so the fingers 10 engage the notches 14 of the nut 13. As will be seen in Fig. 1, the part of the nut 13 between the notches 14 preferably projects beyond the cylindrical surface of the drum 8 so as to prevent any chance of the fingers 10 from springing out of the notches 14. This construction enables me to use a flat lock washer, later referred to, thereby cheapening the cost of the manufacture of

my device. The flat locking washer 15 having slots 16 adapted to receive the fingers 10 is then placed over said fingers and the retaining ring 17, having projections 18 that are adapted to enter the slots 11 in fingers 10, is snapped into position thereby locking the drum 8 and the pinion 5 to the nut 13 hence completing the drive connection between the shaft 3 and the pinion 5.

10 From the above it is seen that my method of fastening the nut 13 to the drum 8 constitutes a quick detachable means for the purpose of easy and rapid assembly and disassembly when necessary.

15 There are other details which enter into the operative connection of the pinion 5 to the shaft 3 which I will now explain. A portion of the shaft 3 is reduced at 19 and on this reduced part is carried a spring 20

20 that is held in place by a washer 22 which in turn is held against the spring 20 by a spring lock 21 that engages a groove in the shaft 3 at the point where the threaded portion 12 and the reduced portion 19 meet.

25 The inner part of the nut 13 has a flange 24 for supporting one end of a spring 25 carried within the drum 8. The other end of the spring 25 rests against the collar 6. The function of the spring 20 will be later

30 referred to. A washer 23 serves as an abutment for the spring 20 at the point adjacent the pinion 5. I prefer in the assembly of my starting device to put a certain initial pressure on the spring 25 so as to always

35 exert sufficient pressure against the parts to prevent them from rattling. This is one of the functions of the spring 25. Between the end of the pinion 5 and the shoulder 26 on the shaft 3 there is a spring 27 for the purpose of keeping the pinion 5 and its associated parts from creeping forward into engagement with the gear teeth 2. I prefer to use a washer 28, resting against the shoulder 26, for the spring 27 to abut against.

40 Coming now to the operation of my starting device, which is shown in its normal position, when the starting motor is operated the pinion 5, on account of the inertia of the pinion 5 and its associated parts, starts

45 advancing longitudinally into engagement with the gear teeth 2. Just previous to the full engagement of the pinion 5 with the gear 2 the flange 24 comes into engagement with the washer 22 and the spring 20 is compressed thereby taking up the shock of engagement. When the engine starts on its own power and the gear 2 begins to travel faster than it was driven by the pinion 5, the nut 13 immediately operates to draw the

50 pinion 5 out of engagement with the engine driven member and under this condition the inner end of the pinion 5 strikes against the washer 23 so that the spring 20 acts to absorb the disengaging "blow" of the starting

device. Should, for any reason, the teeth 65 of the pinion 5 meet end on with the teeth 2 when traveling into engagement thereby preventing its forward travel, the nut 13 will still continue to move forward pushing the drum 8 forward on the teeth of the pinion 5 compressing the spring 25 until this spring has been compressed to a point where it offers sufficient resistance to cause the nut 13 to begin to turn the pinion 5. It will be understood that the pinion 5 will need to 70 move but a little before it will line up with the teeth 2 and it will then, due to the compression of the spring 25 and the action of nut 13, slip immediately into engagement. It is, therefore, seen that spring 25 serves 80 an additional function as just described in addition to the function first mentioned heretofore.

It will be understood that although I have shown my starting device adapted to be engaged with the gear on the fly wheel, that the engine driven member may be some other gear operated by the engine.

In the drawing I have shown a drive of the "inboard" type, that is to say, a type 90 in which the starting pinion is moved toward the starting motor and no bearing is required on the outer end of the driving shaft. It will be understood that my device is readily susceptible to the necessary 95 changes to make it into an "outboard" type, that is to say, one in which the driving shaft has an outboard bearing external to the starting motor, both types being in use in the trade. It is also to be understood that 100 my device is susceptible to other changes as to its details without departing from the spirit of my invention and the scope of the appended claims.

Having thus described my invention what 105 I claim is:—

1. In a starting device the combination of, an engine driven member having gear teeth thereon, a driving shaft having screw threads, a pinion guidingly supported on 110 the shaft, for engagement with the gear teeth of the engine driven member, a nut carried by the screw threads, a drum operatively connected with the pinion and having spaced projections at one end, said nut having 115 projections extending between the drum projections and beyond the outer surface of the drum, means to hold the projections in assembled relation comprising a flat annular washer fitting about the drum projections and behind the nut projections and a snap ring co-operating with the drum projections and holding the washer in place.
2. In a starting device the combination of, an engine driven member having gear 120 teeth thereon, a driving shaft having a smooth portion and a screw threaded portion, a pinion having a smooth bore guid-

- ingly supported on the smooth portion of said shaft for engagement with the gear teeth on the engine driven member, a nut carried on said screw threaded portion of 5 the shaft, a drum slidably connected at one end with the pinion and having spaced projections at one end, said nut having projections extending between the drum projections and beyond the outer surfaces thereof, 10 means for holding the projections in working relationship comprising an annular washer fitting about the drum projections and behind the nut projections and a snap ring coöperating with the drum projections 15 and holding the washer in place.
3. A drive for engine starters comprising a rotatable shaft, a driving member mounted thereon for both longitudinal and rotary movement thereof and rotary movement 20 therewith and adapted to coöperate with and drive a member of the engine to be started, a control member mounted on said shaft for longitudinal and rotary movement thereof and rotary movement therewith, 25 driving means connecting between the driving member and the control member, and a single means serving for stopping said longitudinal movement of the control member back and forth on said shaft.
- 30 4. In a starting device the combination of, an engine driven member having gear teeth thereon, a driving shaft having screw threads, a gear wheel having a small bore slidably supported on the shaft adjacent the 35 engine driven member and adapted to engage the gear teeth thereon, a drum operatively connected at one end to the gear wheel, a nut carried on said screw threads and operatively engaging the other end of 40 said drum and quick detachable means consisting of two elements only, a flat locking washer and a snap ring engaging the outer extremities of the drum whereby the said drum is held in driving relationship between 45 the nut and gear wheel.
5. In a starting device the combination of, an engine driven member having gear teeth thereon, a driving shaft having screw threads, a nut carried on said threads, a 50 gear wheel carrying a collar slidably supported on said shaft adjacent said engine member and adapted to engage the gear teeth thereon, said nut and gear wheel being operatively connected together by a drum 55 having one end fitting in the teeth of said gear wheel and abutting against said collar and the other end fastened to said nut, and a spring within said drum having one end annularly supported by said nut and the 60 other end abutting against said collar, said spring serving to prevent rattle between said parts.
6. In a starting device the combination of, an engine driven member having gear teeth 65 thereon, a driving shaft having screw
- threads, a nut carried on said threads, a gear wheel carrying a collar slidably supported on said shaft adjacent said engine member and adapted to engage the gear teeth thereon, said nut and gear wheel being 70 operatively connected together by a cylindrical drum having one end slidably fitting in the teeth of said gear wheel and abutting against said collar with the other end detachably fastened to said nut, and a spring 75 within said drum having one end annularly supported by said nut and the other end abutting against said collar adjacent the drum end, said spring having a normal tension to prevent rattle between the gear 80 wheel, nut and drum and also serving to permit the nut and drum to advance longitudinally along the shaft should the gear wheel meet with an obstruction in going into engagement with the gear teeth on the engine 85 driven member, whereby when the gear wheel is slightly rotated the compression on said spring will slide the gear wheel quickly into mesh as described.
7. In an engine starter drive including a 90 threaded rotatable member, a driving member mounted thereon for longitudinal movement thereof and rotary movement therewith, said driving member consisting of a nut adapted to travel on the threaded part 95 of said rotatable member, a cylindrically shaped member fastened at one end to said nut and having a gear wheel operatively connected to the other end, a spring within the cylindrical member adapted to exert 100 initial pressure between said nut and gear wheel; and a second spring within the cylindrical member carried on said rotatable member adjacent the threaded part serving as a stop for said nut and driving member 105 in both longitudinal directions of travel as described.
8. In an engine starter drive including a 110 threaded rotatable member, a driving member mounted thereon for longitudinal movement thereof and rotary movement therewith, said driving member consisting of a nut adapted to travel on the threaded part 115 of said rotatable member, a cylindrically shaped member detachably fastened at one end to said nut and having a gear wheel operatively connected to the other end, means within the cylindrical member for exerting an initial pressure between said nut and gear wheel for the purpose described; 120 and means within the cylindrical member carried by said rotatable member for limiting the longitudinal movement of the nut and driving member in both directions.
9. In an engine starter drive including a 125 threaded rotatable member, a driving member mounted thereon for longitudinal movement thereof and rotary movement therewith, said driving member consisting of a nut adapted to travel on the threaded part 130

- of said rotatable member, a cylindrically shaped member fastened at one end to said nut and having a gear wheel operatively connected to the other end, means within the cylindrical member having an initial pressure between said nut and gear wheel for preventing rattle and further for assisting said nut in operating said gear wheel as described; and means carried within the cylindrical member for limiting the travel of said nut longitudinally in two directions.
10. In an engine starter drive including a threaded rotatable member, a driving member mounted thereon for longitudinal movement thereof and rotary movement therewith, said driving member consisting of a nut adapted to travel on the threaded part of said rotatable member, a cylindrically shaped member fastened at one end to said nut and having a gear wheel operatively connected to the other end, means within the cylindrical member having an initial pressure between said nut and gear wheel for preventing rattle and further for assisting said nut in operating said gear wheel as described; and means carried within the cylindrical member for limiting the travel of said nut longitudinally in two directions, and means for preventing said driving member from "creeping" on the rotatable member.
11. In an engine starter drive including a threaded rotatable member, a driving member mounted thereon for longitudinal movement thereof and rotary movement therewith, said driving member consisting of a nut adapted to travel on the threaded part of said rotatable member, a cylindrically shaped member detachably fastened at one end to said nut and having a gear wheel operatively connected to the other end, a helical spring within the cylindrical member annularly supported at one end by said nut and having the other end abutting against said gear wheel and exerting an initial pressure against each; a second helical spring within the first carried on said rotatable member for limiting the longitudinal travel of said driving member and absorbing with the first mentioned spring the shocks of engagement, and a resilient member for preventing the driving member from "creeping" on the rotatable member.
12. In a starting device the combination of, an engine driven member having gear teeth thereon, a driving shaft having a gear wheel carried thereon and adapted to engage with the gear teeth on the engine driven member; said gear wheel being drivingly connected to said driving shaft through the following instrumentalities; a collar attached to the non-working end of the gear wheel, a cylindrical drum having one end perforated to conform to the shape and number of the teeth on the gear wheel and carried thereon, the other end being open with the surface of the drum terminating in slotted fingers, threads on said shaft, a nut carried on said threads and having a notched flange, said notches adapted to receive said fingers of the drum and the material between said notches extending beyond the outer surface of the drum to prevent said fingers from springing out of said notches, a flat annular lockwasher having slots therein to receive the ends of said fingers and a retaining ring having projections adapted to engage the slots in said fingers whereby the drum is locked securely to the nut as described.
13. A starter for gas engines and the like comprising in combination, a driven member operatively connected with the engine, a driving member adapted to coöperate with and drive the other member but normally out of coöperation therewith, shifting means for said driving member operated by a starting motor and a single resilient means for limiting the range of said shifting means in its forward and backward movement.
14. An apparatus of the class described, in combination, an engine driven gear, a driving gear adapted to coöperate therewith, a motor driven shaft having a portion inclined to its axis for effecting the movement of said driving gear into mesh with said driven gear, means for then transmitting torque from said shaft to said driving gear including a rigid member coöperating with said shaft and a resilient stop for limiting the motion of the rigid member and connecting it for operation of the driving gear, said resilient stop serving also to limit the motion of the rigid member when the driving gear is forced out of mesh with the driven gear on the starting of the engine.
15. A starter for gas engines and the like comprising in combination, an engine driven member, a driving member adapted to coöperate with the other member but normally out of coöperation therewith, shifting means for said driving member operated by a starting motor, said shifting means including a flanged nut, a coiled spring between said nut and supported on the flange thereof and said driving gear to transmit longitudinal impulses from said nut to said driving gear to place it in mesh with said driven gear, a drum coöperating with said nut and with the teeth of said driving gear, and a yielding stop to limit the forward longitudinal travel of said nut to compel said nut, said drum and said driving gear to turn with said motor whereby the engine is started, said yielding stop serving also to limit the rearward longitudinal travel of said nut and driving gear when the said gear is expelled from engagement with the engine driven member as the engine starts under its own power.
16. In a starter for gas engine and the like,

a combined shifting and starting member, including a driving pinion, a drum coöperating therewith to drive the same, a flanged rigid member adapted to connect said drum 5 to a motor driven element, a spring interposed between said rigid element supported on said flange and said driving pinion, a flat annular lock washer for maintaining said rigid member against said spring and a snap 10 ring for securing said lock washer in position on said drum.

17. In a starter for gas engines and the like, a combined shifting and starting mem-

ber, including a drum for coöperation with a driving gear, a nut within one end of said drum having portions extending beyond the surface of said drum, said drum having longitudinal fingers within the extended portions of said nut, a flat annular lock washer to assist in holding said nut within said 15 drum having slots through which said fingers may pass and a snap ring coöperating with said fingers for keeping the lock washer in place.

In witness whereof, I affix my signature.

JULIUS H. RICHARDS.
